GAME

Filed Dec. 28, 1927

FIG. 1.

Neville C. Seymour, INVENTOR

BY *Neville C. Seymour*

WITNESS:

John G. Evans

ATTORNEY

UNITED STATES PATENT OFFICE

NEVILLE C. SEYMORE, OF JERSEY CITY, NEW JERSEY

GAME

Application filed December 28, 1927. Serial No. 243,189.

The present invention relates to an improved game, more especially to a railroad type of game, wherein a member may be rolled or worked over the board through a plurality of wickets, from a starting point to a certain destination according to the course of travel of a person over a certain railroad route.

Another purpose is to provide a game which is fascinating, interesting and educational, not only with regard to the various places or stations or towns through which a train passes but also with regard to other towns in the vicinity of those through which the train is passing.

A further purpose is to provide a game of this character which is not only tedious to cause the rolling member to traverse the game board in the proper direction, but tends to show how steady a person's hand might be in manipulating and whether the person possesses a substantial degree of equilibrium.

A still further purpose is to provide a game including a starting base or point, a route, which may correspond to the railroad route to be traversed by the person operating the game, in conjunction with a goal at the terminal of the route the aim being to carry the rolling member from the starting point in the right direction through the wickets at certain towns or cities, according to a dotted line indicating a course of travel, corresponding to the route.

It is to be understood that the particulars herein given are in no way limitative, and that while still keeping within the scope of the invention, any desired modification of details and proportions may be made in the construction of the appliance according to circumstances.

The invention comprises further features and combination of parts to be hereinafter set forth, shown in the drawings and claimed.

In the drawings:

Figure 1 is a plan view of the game board showing a map on which a railroad route is indicated illustrating the wickets and the starting point and the goal.

Figure 2 is a longitudinally sectional view on line 2—2 of Figure 1.

Referring to the drawings, 1 identifies a game board, which comprises a base 2, which may be constructed of any suitable material preferably wood or fabric and secured to the under face of the board 2 is a paper or card-board facing 3, which turns up on the sides and ends of the board to provide marginal flanges 4 and 5, the flanges 4 being at the ends of the game board, while the flanges 5 extend along the longitudinal edges of the game board.

A suitable card-board or paper cover 6 relatively thick, substantially corresponding to the thickness of the flanges 4 and 5 is provided.

Fastened in any suitable manner, preferably adhesive is a map 9 constructed of paper or a composition of paper and linen or paper backed with linen, and the map as disclosed in Figure 1 may correspond to a fascinating railroad route to be traversed by the operator. The fact is the game board may be constructed according to various routes of a particular railroad.

It is obvious that the invention is not to be limited to any particular route. It is the purpose in providing a game of this character to have a number of games on which the routes may correspond to the various routes of a railroad, so that a traveler may purchase a game according to the course of travel to be taken, and while sitting in the car it is the aim to carry a rolling ball 10 along the route disclosed on the map.

In different locations, especially at important towns or cities upright wickets 11 are mounted. These wickets may be driven into the board so that they will stand upright and provide for free passage of a spherical roll-

ing member 12. The game board has a starting point 13 at the beginning of the route and a terminal point 15 at the end of the route. The fact is these starting and ending points 5 are in the form of cavities formed in the game board.

Rules of play

The ball or spherical member 12 is placed 10 in the cavity or starting point 13, and then the ball is guided through the various wickets, the operator manipulating the board so as to cause the spherical member or ball to roll out of the cavity 13 and carried through 15 the several wickets according to the dotted line 16, and when the ball or spherical member reaches the cavity 14, without passing through the wickets in the wrong direction other than that indicated by the dotted line, 20 the game is won by the operator. It is possible to use the game on railroads, and when there is more than one traveling in company, say for instance two persons, it is possible for the persons to compete.

25 It is necessary to permit the spherical member or ball to pass through any wicket in the proper direction, but should the ball pass through a wicket in a reverse direction other than that shown will require a new attempt 30 from the starting point. This spherical member or ball cannot pass through a wicket from either side. The ball or member must pass through the wicket in the direction of the arrows 17 disclosed on the dotted line 16. Failure to observe any of these rules requires a new attempt from the starting point. The 35 present game is favorable for various gatherings and those who pass through the wickets incorrectly may be subjected to a penalty. However when wickets are passed 40 through properly in correct order the player is exempt from penalty.

The purpose of this game is to complete the course of travel as rapidly as possible, and a 45 little practice will enable an operator to show that considerable skill can be developed. As previously stated competition among several players proves most entertaining, to see who can lower the record time.

50 The invention having been set forth, what is claimed is:

A game comprising a game board having a perfectly smooth flat plane surface, and a plurality of wickets positioned at predetermined varied irregular locations on said 55 smooth flat plane surface of the board, and a line consisting of broken arrows indicative of an irregular route to define an uninterrupted direction of irregular travel passing 60 through the irregularly located wickets, an arrow head adjacent each wicket indicative of the direction of passage through said wicket, said line of direction arrows having starting and ending points, said game board being 65 manually tilttable whereby a rolling mem-

ber is operable to move on the plane surface of the board and adapted to pass through the wickets according to the direction of travel indicated by the arrow heads adjacent the wickets, the passage of the rolling member through any wicket backwards or out of order of travel indicated by the line of broken arrows penalizing the player to retraverse said line of broken arrows.

In testimony whereof he affixes his signature.

NEVILLE C. SEYMOUR.
